UNITED STATES PATENT OFFICE.

THOMAS C. WHITEHEAD AND FRED J. HEIDEMAN, OF DETROIT, MICHIGAN; SAID HEIDEMAN ASSIGNOR TO SAID WHITEHEAD.

PUMP-VALVE ASSEMBLY.

Application filed July 6, 1926. Serial No. 120,709.

This invention relates generally to pump valve assemblies, particularly designed for refrigerating apparatus, and consists of certain novel features of construction, combinations and arrangements of parts as will be more fully described and particularly pointed out in the appended claims.

In the accompanying drawing:

Figure 1 is a fragmentary side elevation 10 of a pump embodying our invention.

Figure 2 is a top plan view thereof.

Figure 3 is a fragmentary sectional view taken on the line 3—3 of Figure 2.

Figure 4 is a view similar to Figure 3 but 15 showing a slightly modified form of follower.

Referring now to the drawing, 1 is a pump cylinder in which the gas is adapted to be compressed, 2 is a plate having a series of 20 openings 3 arranged in a circle and constituting outlet ports for the cylinder, and 4 is a detachable head having a central exhaust passage 5 for the compressed gas. As shown, the plate 2 has an annular recess 6 25 in its upper face and is preferably provided between the openings 3 and the upstanding walls 7 of the recess with a rounded ridge or bead 8 that serves as a bearing or seat for a metal wafer valve 9. Preferably the base 10 of the recess 6 is flat and is lower than the 30 ridge 8 which surrounds the openings 3.

To provide an efficient construction the valve 9 is preferably formed from light gauge sheet metal and is substantially equal 35 in area to the area of the recess 6. Normally the central portion 11 of this valve is yieldably held upon the flat base 10 of the recess so that the marginal portions 12 will be seated firmly but will be free to move 40 upwardly from the ridge or bead 8. This is accomplished by providing an inverted substantially T-shaped follower 13 that is pressed against the valve 9 by a relatively heavy coil spring 14. As shown, the base 15 of the follower is circular in form and is 45 centered in the recess 6. Preferably the lower face of the base 10 inclines upwardly from its center to the edge portions 17 which in turn are preferably rounded as shown to 50 permit the marginal portions of the valve to flex gradually when unseated by the compressed gas. Preferably the coil spring 14 is sleeved upon the upstanding arm 18 of the follower and engages the base 19 of a 55 recess 20 in the cylinder head 4. As shown

in Figure 3, this recess 20 has a frusto-conical portion 21 that is in alignment with the passage 5 and receives the upper end of the spring 14, and has an annular portion 22 that receives the base 15 of the follower. 60 Preferably this base has an upstanding marginal flange 23 that is in alignment with an annular shoulder 24 provided between the frusto-conical and annular portions 21 and 22 respectively of the recess 20. 65

In Figure 4, we have shown a slightly modified form of follower 30. With this construction, the base 31 of the follower is provided adjacent to the peripherally rounded edge portions 32 thereof, with a rounded 70 ridge or bead 33 that engages the valve 9 adjacent to the openings 3.

In use, the gas in the cylinder 1 will be forced upwardly by a suitable piston (not shown) through the openings 3 in the plate 75 2, and after unseating the marginal portions 12 of the valve, will flow upwardly through the recess 20 and out through the passage 5 in the cylinder head. Inasmuch as the area of the valve 9 and follower 13 or 30 is relatively large, it will be apparent that less resistance is set up and as a result only one 80 spring is required. Moreover the openings 3 will break up the compressed gas into smaller particles which will pass by the valve 85 9 without creating objectionable noise. It will also be noted that the ridge or bead 8 provides a line contact for the valve which is particularly desirable when the same portion of the valve can seat upon the same line 90 at all times. Inasmuch as the base 11 of the recess is lower than the ridge 8 it will also be apparent that the marginal portions of the valve will have a tendency to seat firmly 95 upon the ridge when the follower is seated upon the central portion of the valve. Furthermore the rounded edge portions of the base 10 not only permit the marginal portions of the valve to flex gradually when unseated, but also acts as a stop to limit such flexing of the valve. Aside from these features the construction set forth herein comprises relatively few parts and therefore can be manufactured at a comparatively low cost. 100

While it is believed that from the foregoing description, the nature and advantage of our invention will be readily apparent, we desire to have it understood that we do not limit ourselves to what is herein shown 110

and described and that such changes may be resorted to when desired as fall within the scope of what is claimed.

What we claim as our invention is:

- 5 1. A valve assembly comprising a plate having an annular recess in its upper face and openings arranged in a circle in the base of said recess adjacent to the walls thereof, a flexible disk valve in said recess 10 having marginal portions for controlling the flow of fluid through said openings, yieldable means normally retaining said valve in said recess, and a ridge on the base of said recess normally retaining the marginal portions 15 of said valve in elevated position with respect to the central portion of said valve.
2. A valve assembly comprising a plate having a recess therein, a ridge adjacent to the side wall of said recess, and a series of 20 openings arranged in a circle of the base of said recess, said base being lower than said ridge, a disk valve in said recess, and a spring pressed follower normally holding the central portion of said disk valve against 25 the base of said recess in a flexed condition so that the marginal portions of said valve will firmly seat upon said ridge.
3. A valve assembly comprising a member having a fluid passageway therethrough and 30 having a raised annular seat surrounding said passageway, a disk valve having its marginal portions seated upon said annular seat and means for resiliently holding the inner portion of said valve disk against said member thereby maintaining the disk in a

flexed condition with its marginal portions free to become unseated upon further flexing thereof.

4. A valve assembly comprising a member having a raised annular seat, a flexible disk 40 valve having its marginal portions seated upon said annular seat and means for resiliently holding the inner portion of said valve disk against said member thereby normally maintaining the disk in a flexed condition, said member having an annular series 45 of fluid passageways therethrough adjacent said seat and arranged within the area bounded by said annular seat.

5. A valve assembly comprising a plate 50 having a plane surface and having an annular ridge surrounding said plane surface, said plate also having a series of openings 55 therein extending through said plane surface within the area bounded by said annular ridge, a flexible disk valve for controlling the passage of the fluid through said openings, having marginal portions resting upon said annular ridge and yieldable means pressing the central portion of said valve 60 disk against said plane surface thereby normally maintaining said disk valve in a flexed condition with the marginal portions thereof held against said ridge and free to become unseated upon further flexing thereof. 65

In testimony whereof we affix our signatures.

THOMAS C. WHITEHEAD.
FRED J. HEIDEMAN.
